YASUJIRO KINOSHITA, OF KOISHIKAWA-KU, TOKYO, JAPAN

SUBMERSIBLE BOAT

Application filed March 31, 1931, Serial No. 526,608, and in Japan April 25, 1930.

This invention relates to a submersible boat which travels through the waves in a partially submerged condition. The objects of the invention, among others, are as follows:

Firstly, the body of the boat is made long and narrow in shape which, combined with its sharp edged fore and aft ends offers a minimum resistance of water while the total weight of the boat and its contents being made a little less than its buoyancy it is always kept in a partially submerged condition so that it is not affected by the rough actions of the wind and waves that it is to encounter on its high speed passage. The boat consists of a number of sections joined together in a straight line in such a way that it is made bendable horizontally at the junction where two ends of the sections meet, thus aiding to preserve its stability and to travel at high speed.

Secondly, on both sides of the jointing part of each section is fixed a stop plate extending over the end of the successive section, forming a shape of a pair of opened scissors, by means of which the turning angle at the junction is restricted within a certain limit of allowance, and on the front and rear parts of the boat are provided a propeller respectively, so that by adjusting the speed of the revolution of the propellers the function of the rudders can be redoubled and consequently the course of the boat can be changed quickly and accurately.

Thirdly, the stern section of the boat is made bendable perpendicularly at the junction so that the rear part of the boat can be brought on the beach just as it is.

This invention is explained by reference to the accompanying drawings, in which:

Figure 1 represents a side view of the entire boat.

Figure 2 represents a side view showing the jointing part of two sections.

Figure 3 represents a plan view showing the jointing part of two sections.

Figure 4 represents a side view showing the stem section chiefly.

Figure 5 represents a plan view of Figure 4.

Figure 6 represents a front view of the entire boat.

This invention consists in a boat (A) forming a long and narrow shape, its total weight being made a little less than its buoyancy, and its body being built in several sections (1)—(1) joined together in a straight line and made to be bendable horizontally at the junctions (5), and the end of its stern section as well as that of the stem section being made sharp edged, and a pair of suitably located stop plates (6) extending from the outsides of the end part of one section towards its successive section, the inner face (7) of one of the opened scissor like stop plates being arranged to come in contact with the outer surface of either side of the end part of its successive section so that the turning angle of the joining section, on which the two stop plates are fixed, with the joined one being restricted within a certain limit of allowance.

On the outer surface of the front part as well as the rear part of the boat is respectively provided a propeller (9) (11) having blades (8) girded by a span plate (10), fixed on the outer surface of each of the sections so as to reenforce the parts of the boat where the propellers are attached. In case of a larger sized boat more propellers may be fixed on intermediate sections so as to counteract the friction, resistance or like action on the sides. The stem section is provided with a mast (2), which can be set up right or down when required, and at the top of the lower mast is suspended an observation basket (3), in which an observer may be stationed on lookout, and from which a lookout kite (12) may be flown up. The boat is provided with rudders (14) (14') (14'') by means of which its stability can be ensured. Each of the sections has a ventilator for exhaustion as well as for air supply. However, a device may be arranged for the exhaust of the engine to vent into the water. The stern section is bendable perpendicularly at the junction where it is connected with the preceding section, so that when the boat goes astern it can get on the beach by itself, thus facilitating the connection be-

tween the boat and shore. For this purpose it is advisable to have rollers provided on the bottom of the stern section.

This invention is, as shown in Fig. 1, to 5 construct a submersible boat which floats in a partially submerged condition, which by operation of both front and back propellers (9) (11) can travel through the waves at high speed, and which can be stabilized by 10 steering the vertical and horizontal rudders, the former serving to direct the course of the boat simply and quickly and the latter serving to keep the body of the boat in vertical equilibrium. The vertical equilibrium 15 may, however, be advantageously maintained automatically by means of a mechanical device.

When the course of the boat is to be 20 changed the operation of the front propeller is suspended or the speed of its revolution is reduced, the stern section being steered a little in the direction required by means of the rudder (14') so that the profile of the stern being resisted by the water due to the inertia 25 force of the boat going forward it will begin to turn within the limit of allowance restricted by either of the stop plates (6), the succeeding sections gradually following the changed course.

30 The boat can be moored to an anchor buoy in an ordinary manner. It would, however, be more advantageous than otherwise to have the stern section of the boat got on the beach, not only for facilitating the connection between the boat and shore, but also for adjusting 35 the engine by clearing the covering part of the boat. The boat has another advantage in ensuring more stability of the body, preventing any oscillations by making the 40 boat curved at the junctions when the boat is stopped.

Having thus described the invention, what I claim is:—

1. A submersible boat which travels 45 through the waves in a partially submerged condition, characterized in that it consists of a number of long, narrow and cylindrically shaped sections, the total weight of which is made to be a little less than its buoyancy, that 50 both front and back parts of the boat are provided with propellers, and vertical and horizontal rudders, and that each of the sections is provided with a ventilator for air supply and exhaustion.

55 2. A submersible boat as claimed in claim 1 and further characterized in that both stem and stern ends of the boat are made sharp edged so that by slightly turning the direction of the stem section and by adjusting the 60 speed of revolutions of the propellers at the front and back parts of the boat, the course of the whole body of the boat can easily be changed as desired.

65 3. A submersible boat as claimed in claim 1 and further characterized in that the outer

surface of the boat is provided with propellers having blades, over which a span plate is secured respectively for reinforcement purpose.

4. A submersible boat as claimed in claim 70 1 and further characterized in that on both sides of one end part of each section is fixed a stop plate respectively which restricts the turning angle at the junction within a certain limit of allowance, the inner face of one 75 of the stop plates coming in contact with the outer surface of the end part of the successive section.

5. A submersible boat as claimed in claim 80 1 and further characterized in that the stern section of the boat is made to be bendable at the junction so that the back part of the boat can be got on the beach by itself.

In testimony whereof I have affixed my 85 signature.

YASUJIRO KINOSHITA.
